UNITED STATES PATENT OFFICE.

FRED E. BURLINGAME, OF PAWTUCKET, RHODE ISLAND, ASSIGNOR TO ATTLEBORO BRAIDING CO., OF SOUTH ATTLEBORO, MASSACHUSETTS, A CORPORATION OF MASSACHUSETTS.

LACING-TIPPING MACHINE.

Application filed June 11, 1924. Serial No. 719,299.

This invention relates to an improved machine for forming tips on lacings such as shoe lacings, corset lacings, and the like, and the object of this invention is to provide such a machine that will wrap or fold the lacing fabric about a stiffening core where it is retained by cement.

A still further object of the invention is the provision of a set of cooperating dies for wrapping the fabric about the core and a cutter for cutting the tip in two.

A still further object of the invention is to provide a pair of dies having a space between them into which the lacing fabric and its core are deposited, also to provide a locking or retaining plate for securing the fabric and core in operative position in this space between the dies and to provide means for imparting a relative closing movement to the dies for wrapping the fabric about the core while confined in the space between the dies.

With these and other objects in view, the invention consists of certain novel features of construction, as will be more fully described, and particularly pointed out in the appended claims.

In the accompanying drawings,

Figure 1 is a top view of my improved tipping machine partly broken away to better illustrate the action of the dies.

Figure 2 is a central sectional elevation through the machine showing the double action of the operating lever.

Figure 3 is a perspective view illustrating the die plates and cutter.

Figure 4 is a perspective view showing the core locking plate in detail.

Figure 5 is a section on line 5-5 of Figure 2, showing the yieldable means for permitting the core locking plate to be lifted over the core.

Figure 6 is an enlarged sectional view showing the core as deposited on the fabric which lies in curved position between the dies.

Figure 7 shows the core locking plate as raised to slide up over the core and lacing by riding over its cam.

Figure 8 shows the core locking plate in locked position with its locking arms.

Figure 9 shows the dies as having been ad-

vanced and as having wrapped the fabric about the core in which position it is held until the cement, with which the fabric is treated, is dried.

Figure 10 is a perspective view showing the tipped end of a lacing with the core in position and before the fabric has been wrapped about the core.

Figure 11 shows the fabric as having been wrapped around the core of double length to be later severed by the cutter.

In the forming of lacing tips by my improved machine the lacing is led by a continuous method explained in my co-pending application, Serial No. 722,581, filed June 26, 1924, to this machine, and is treated at intervals with cement for a short distance, about double the length of a single tip. The next feeding movement of the fabric brings this treated section into the space between the dies of my improved tipping machine in a curved condition, that is crescent shape or concavo-convex in cross section and into this curved and cement-treated portion of the lacing I deposit a short length of stiffening material, preferably soft metal wire. The locking plate is then carried forward to cover the space occupied by the core and lacing, to lock the same between the dies, the dies then receive a relative closing movement which wraps the lacing fabric about the core and at the same time severs the double length of tip, the dies retaining the fabric in this wrapped condition until the cement is hardened, which action is hastened by the application of heat thereto; and the following is a detailed description of the embodiment of my present invention:

With reference to the drawings, 15 designates the frame of the machine, which is provided with a pair of dovetailed ways 16 in which the slide plate 17 is slidably mounted. On the forward end of this plate is mounted a pair of die plates 18 between which is located the cutter bar 19. This plate is provided with an opening 20 through which the lever arm 21 operates and the rear end of this plate is tapped as at 22 to receive an adjustable bolt 23 by which the extent of the withdrawing motion of this plate is regulated. This plate

is provided with a hardened contact bar 24 which is engaged by the operating edge 25 of the hardened contact block 26 on the lever 21. The frame of the machine is also provided with a pair of cooperating die plates 27 which are fixed thereto by screws 28, which plates are spaced slightly apart to receive the cutter bar 19 between them and these die plates serve not only to cooperate with the die plates 18 in folding the fabric about the core but also cooperate with the cutter bar to sever or cut in two the double length of tip.

In operating this machine, when the die plates 18 are withdrawn from operating position, a space 29 is provided between them into which the next length of the fabric to be operated upon is drawn, the fabric 31 is curved by suitable means described in my copending application, Serial No. 722,581, filed June 26, 1924, into substantially crescent shape in cross section, and when in this position the core 30 is deposited into this curved and cement-treated portion of the lacing. The core is of such a size relative to the width of the fabric that the edges of the fabric completely surround and abut when folded about the core.

It is found, in order to retain this core and its lacing firmly in position during the action of the cutter 19 and the action of the dies 18 and 27 in folding the fabric about the core, of advantage to cover this space 29, which is accomplished by the provision of plate 32 which is mounted to slide on the slide plate 17 and in order to lift the forward end of this plate 32 over the core this locking plate is provided with laterally-extending bearing lugs 33 which ride up over the cam 34 thus lifting the forward end of this locking plate over the core and after having been lifted thereover the end 35 of this locking plate is then forced beneath the guide arms 36 to press or force the core member 30 downward into the cement and the curved portion of the fabric.

The rear portion of this plate 32 as best illustrated in Figure 5, is pressed downwardly into sliding engagement with the slide plate 17 by means of a bow spring 37 which is mounted on the cross bar 38 and the tension of this spring may be adjusted by the screw 39.

This lock plate is provided with an opening 40 through which the operating lever 21 also extends, the opening in this plate 32 being considerably shorter in length than the opening 20 in the slide plate 17, whereby the first movement of this operating lever 21 actuates this locking plate 32 to first lift it over the core and then force it beneath the guide bars 36, then a continued forward movement of this lever causes the portion 35 thereof to engage the portion 24 of the slide plate 17 which advances this

plate and causes the die plates 18 and 27 to engage the fabric and wrap the same about the core.

In order to operate this lever 21, I have mounted, as is best shown and described in my co-pending application Serial No. 722,581, filed June 26, 1924, a pair of cams which engage this roll 41 at the upper end of this lever, to move it into and out of operating position.

The lower end of this lever is pivoted at 42 on the adjustable block 43, which block is held by the binding screw 44 which may be loosened to permit the adjustment through the screw 45 to regulate the effective stroke of the lever 21.

It has been found in practice of advantage to provide heat in my improved tipping machine and I have herein shown an electric heater 46 which heats the machine and especially the dies and serves to greatly hasten the drying action on the cement.

My improved lacing tipping machine is very simple and practical in construction and effective in its operation and by its use the tips may be formed on the lacing successively by a simple operation of a single lever which is caused to hold the fabric about the core, cut it in two, and also retain the folded fabric on the core until the cement has dried.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a lacing tipping machine, a set of plates of substantially the same thickness lying in substantially the same plane and having recessed edges forming cooperating dies, and means for imparting a relative movement to said dies for folding the lacing fabric about a stiffening core.

2. In a lacing tipping machine, a set of plates of substantially the same thickness lying in substantially the same plane and having recessed edges forming cooperating dies, a cutter blade carried by one of said dies, and means for imparting a relative closing movement to said dies to sever and fold the lacing fabric about a core.

3. In a lacing tipping machine, an operating lever, means responsive to the initial forward movement of said lever for locking a lacing and its core in position to be operated upon and means responsive to a subsequent forward movement of said lever for folding said lacing about its core.

4. In a lacing tipping machine, a pair of dies between which the lacing fabric and its core are deposited, means for locking the

core and lacing in position between said dies, and means for subsequently operating said dies while said locking means is in position for folding the lacing about its core.

5 5. In a lacing tipping machine, a pair of dies between which the lacing fabric and its core are deposited, a lock plate for securing the fabric and core in position between the dies, a cutter for severing the tip portion, and dies for folding the fabric about the core.

10 6. In a lacing tipping machine, a bed plate, a set of co-operating dies relatively movable thereon, a core holding plate for closing the entering opening to said dies, and means for moving said plate and subsequently said dies to operating position during one continuous forward movement 15 of said moving means.

20 7. In a lacing tipping machine, a bed plate, a pair of dies movable thereover and providing a space between them for the reception of the lacing fabric and its core, an overlying top plate for confining said core and fabric in said space, and means for moving said dies relatively to force the fabric about the core within the confined space.

25 8. In a lacing tipping machine, a bed plate, a pair of dies movable thereover and providing a space between them for the reception of the lacing fabric and its core, a top plate, means for lifting said plate over the core and advancing it into position to

overlie said space, and means for moving 35 said dies relatively to force the fabric about the core within the confined space and cause its edges to abut.

9. In a lacing tipping machine, a set of cooperating dies for wrapping the lacing material about the core, a locking plate for holding the core in position, a cutter for severing the tip, a lever, and means whereby the continuous forward movement of said lever positions the locking plate, severs the 40 tip, and causes the dies to wrap the fabric 45 about the core.

10. In a lacing tipping machine, a bed plate, a set of cooperating dies relatively movable thereover, a core locking plate 50 movable over said dies to close the entering opening therebetween, a member for holding said plate in locking position, and means for positioning said locking plate under said member and subsequently operating 55 said dies to fold the lacing fabric about a core.

11. In a lacing tipping machine, a bed plate, a set of cooperating dies operable therewith for wrapping or folding the lacing material about a stiffening core, and means in said bed plate for heating the lacing and said dies during the operating 60 movement of said dies.

In testimony whereof I affix my signature.

FRED E. BURLINGAME.
